UNITED STATES PATENT OFFICE.

MARY ALICE KOHAWN COBURN LAMBERT, OF CHICAGO, ILLINOIS.

DESIGN FOR A COVER FOR COOKING UTENSILS.

SPECIFICATION forming part of Design No. 33,984, dated January 29, 1901.

Application filed November 23, 1899. Serial No. 738,109. Term of patent 14 years.

To all whom it may concern:

Be it known that I, MARY ALICE KOHAWN COBURN LAMBERT, a citizen of the United States, residing at Chicago, in the county of Cook and State of Illinois, (post-office address Varsity Building, Sixty-first street and Ellis avenue,) have invented and produced a new and original Design for Covers for Cooking Utensils, of which the following is a specification, reference being had to the accompanying drawings, which form a part hereof.

In said drawings, Figure 1 represents a perspective view of a cover embodying my design. Fig. 2 is a plan view of the same, and Fig. 3 a sectional elevation thereof.

The material or essential features of my design, as shown in the drawings, consist of an arch-like cover A, adapted to bridge or span the top of a pan or other cooking utensil, with its sides a resting on the pan, said sides rising rather abruptly a short distance from the lower edges thereof and then grad-

ually ascending to the highest point or apex of the cover, and also gradually broadening as they approach said apex until within a short distance from the center, where there is an inward turn or indentation in the edges thereof, as at a'. On the lower edges of the cover eyes or sleeves a² are provided, as shown. 30

The interior of the cover, as will be seen, has a smooth unobstructed radiating surface throughout.

Having thus described my invention, what I claim as new, and desire to secure by Letters Patent of the United States, is—

The design for a cover for cooking utensils, substantially as herein shown and described.

In testimony whereof I affix my signature in presence of two witnesses.

MARY ALICE KOHAWN COBURN LAMBERT.

Witnesses:

M. E. FOWLER,
OSGOOD H. DOWELL.
